CLAIM

The ornamental design for a propeller shield apparatus for a trolling motor, as shown and described.

DESCRIPTION

FIG. 1 is a right side view of a propeller shield apparatus for a trolling motor;

FIG. 2 is a left side view of the propeller shield apparatus for a trolling motor;

FIG. 3 is a rear view of the propeller shield apparatus for a trolling motor;

FIG. 4 is a front view of the propeller shield apparatus for a trolling motor;

FIG. 5 is a top view of the propeller shield apparatus for a trolling motor; and,

FIG. 6 is a bottom view of the propeller shield apparatus for a trolling motor.
